UNITED STATES PATENT OFFICE.

ISAAC NEWTON HALEY, OF PHILADELPHIA, PENNSYLVANIA.

NAIL-PULLER.

1,074,617.

Specification of Letters Patent.

Patented Oct. 7, 1913.

Application filed September 30, 1912. Serial No. 723,145.

To all whom it may concern:

Be it known that I, ISAAC N. HALEY, a citizen of the United States, residing at Philadelphia, in the county of Philadelphia and State of Pennsylvania, have invented 5 certain new and useful Improvements in Nail-Pullers, of which the following is a specification.

My invention relates to improvements in 10 nail pullers, the object of the invention being to provide a device of this character which insures a firm gripping of the nail to compel the extraction of the latter when the device is operated.

15 A further object is to provide a nail puller which embodies two nail gripping members with a longitudinally movable handle mounted to move between the members and having a wedge portion to compel the members to tightly grip the nail when the handle is forced downwardly.

20 A further object is to provide a nail puller of this character which is comparatively simple in construction, neat and attractive 25 in appearance, and strong and durable in use.

With these and other objects in view, the 30 invention consists in certain novel features of construction and combinations and arrangements of parts as will be more fully hereinafter described and pointed out in the claims.

In the accompanying drawings: Figure 1 is a view in side elevation illustrating my 35 improved nail puller in operative position, the upper end of the handle being broken away. Fig. 2 is a view in cross section on the line 2—2 of Fig. 1. Fig. 3 is a fragmentary view in longitudinal section 40 through the base member illustrating the nail gripping members and the handle in elevation with the parts in the same position as shown in Fig. 1. Fig. 4 is a perspective view of one of the nail gripping 45 members. Fig. 5 is a broken perspective view of the handle. Fig. 6 is a perspective view of the other gripping member. Fig. 7 is a broken perspective view of the base member, and Fig. 8 is a perspective view 50 of the side plate 14.

My improved device comprises a base member 1 which is in the form of a casting 55 having parallel sides 2, 2, formed with longitudinal slots 3 therein and integral with a curved claw 4 at one end and a milled hammer head 5 at its other end. The ham-

mer head 5 has cast therein a bar 6 of extremely hard metal which extends at both ends beyond the base and is adapted to be used for depressing the wood at the sides 60 of the nail head 10 to form an entrance for gripping jaws 7, 7, at the ends of my improved gripping members 8 and 9 respectively. The gripping members 8 and 9 are pivotally supported adjacent their lower 65 ends by rivets 11 which are extended through registering openings 12 and 13 in the base 1 and members 8 and 9 respectively, and also through openings in a covering plate 14 which is located at one side of the 70 base 1 and extends above the base opposite an integral extension plate 14^a on the base 1, as seen most clearly in Figs. 1, 3, and 7.

The upper end of base 1 on the shorter side thereof, is recessed as shown at 3^a to 75 form an entrance for the slot 3 which facilitates the assembling of the parts as will more fully hereinafter appear. The base 1, adjacent its upper end, is provided with openings 15 to receive rivets 16. These rivets 16 are also projected through the plate 14, and they extend through slots 17 in members 8 and 9 respectively, so that they limit the pivotal movement of the members.

Between the members 8 and 9, my improved handle 18 is positioned, and comprises a bar having a longitudinal slot 19 therein through which a rivet 20 connecting the upper ends of plate 14 and extension 14^a project. The lower end of the handle 18 is 90 provided with a transversely projecting block 21 which is movable in the slots 3, and may be readily positioned in the slot at the recess 3^a, and this lower portion of the handle is enlarged transversely forming a 95 wedge 22, the edges of which engage the inner edges of members 8 and 9 above the pivotal points of the latter, so that when the handle is forced downwardly, this wedge 22 serves to force the upper portion of the members 8 and 9 apart and press their 100 lower ends together, so that the jaws 7, 7, securely grip the nail. The upper end of plate 14 is thicker than the lower portion forming a shoulder 14^b which fits over the 105 upper edge of the casting at one side and closes the upper recessed end 3^a of slot 3.

The members 8 and 9 are bowed between their ends and member 8 is bifurcated as shown at 23 to straddle the handle 18 and 110 allow the members to be gripped at opposite sides of the handle to readily manipulate

the members to separate the jaws 7 when one hand is gripped around the upper ends of the members 8 and 9 and the handle 18. In other words, in operating the device, one end is gripped around the upper ends of the members 8 and 9 to draw them toward the handle, thus spreading the jaws 7, 7, apart, it being of course, understood that the handle 18 is elevated.

10 When the jaws are positioned beside the head of the nail, the handle 18 is forced downwardly, and a suitable tool may be used to hammer the handle downwardly if desired. This downward movement of the handle, as above explained, through the medium of the wedge shaped portion 22, compels jaws 7, 7, to grip the nail. When in this position, the handle 18 is drawn to one side with the claw 4 as a fulcrum, so 15 that the nail is drawn out of the wood. If the nail be long, and the movement above described does not draw it entirely out of the wood, the head may be gripped by the claw and the hammer end 5 operated as a 20 fulcrum to draw the nail entirely out of the wood.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

35 Having thus described my invention, what I claim as new and desire to secure by Letters Patent is:

1. A nail puller comprising a base member having parallel slotted sides, and side plates at opposite sides of the base member, nail gripping members pivotally connected to the base member and having slots therein above other pivotal connection, devices projected through the base member and the 40 side plates and through the slots in the nail gripping members, a handle member positioned between the nail gripping members and having a wedge shaped enlargement adapted to engage the nail gripping members, a transverse bar on the handle movable in the slots in the casting, said handle 45

having a longitudinal slot therein, and a rivet projected through the upper ends of the side plates and through said slot in the handle, substantially as described.

2. A nail puller comprising a base having an extension thereon constituting a fulcrum, nail gripping members pivotally supported by the base, and a wedge shaped handle connected to the base and movable longitudinally between the nail gripping members, whereby the movement of the handle in one direction forces the ends of the nail gripping members toward each other, substantially as described.

3. A nail puller comprising a base having an extension thereon constituting a fulcrum, nail gripping members pivotally supported by the base, and a wedge shaped handle connected to the base and movable longitudinally between the nail gripping members, whereby the movement of the handle in one direction forces the ends of the nail gripping members toward each other, and said nail gripping members extended above the 75 base and adapted to be moved toward the handle to move them apart at their nail engaging ends, substantially as described.

4. A nail puller comprising a base having an extension thereon constituting a fulcrum, 80 nail gripping members pivotally supported by the base, and a wedge shaped handle connected to the base and movable longitudinally between the nail gripping members, whereby the movement of the handle in one direction forces the ends of the nail gripping members toward each other, and said nail gripping members extended above the base and adapted to be moved toward the handle to move them apart at their nail engaging ends, one of said nail gripping members bifurcated at its upper end and adapted to receive the handle in said bifurcated end, substantially as described.

In testimony whereof I have signed my 95 name to this specification in the presence of two subscribing witnesses.

ISAAC NEWTON HALEY.
